UNITED STATES PATENT OFFICE.

GEORGE H. FERNALD, OF NORTH EAST, PENNSYLVANIA.

DESIGN FOR A SPRING FOR ANTIRATTLES.

SPECIFICATION forming part of Design No. 31,945, dated December 5, 1899.

Application filed October 14, 1899. Serial No. 733,675. Term of patent 7 years.

To all whom it may concern:

Be it known that I, GEORGE H. FERNALD, a citizen of the United States, residing at North East, in the county of Erie, State of Pennsylvania, have invented and produced a new and original Design for a Spring for Antirattlers for Thill-Couplings, of which the following is a specification, reference being had to the accompanying drawing, forming a part thereof, and in which I show an isometrical view of the spring detached.

As shown in the drawing, the leading or material feature of my design comprises a strap-spring, the body *a* of which is in the

form of an arc of a circle and terminating at 15 one end in an eye *b* and at its opposite end in a reentrant arm *c*.

Having described my invention, what I claim as new, and desire to cover by Letters Patent, is—

The design for a spring for an antirattler, as herein described and shown.

In witness whereof I have hereunto set my hand this 3d day of October, 1899.

GEORGE H. FERNALD.
